UNITED STATES PATENT OFFICE.

GEORGE SIDNEY MEPESTEAD, OF LONDON, ENGLAND.

ROTARY PUMP.

Application filed October 9, 1926, Serial No. 140,576, and in Great Britain November 30, 1925.

This invention relates to rotary pumps of the type in which the pump chamber comprises an annular compartment around which is adapted to travel a piston or radial 5 blade member, the chamber having inlet and outlet ports associated with it.

The object of the present invention is to incorporate in a pump of this type certain features which provide a combination resulting in a highly efficient pump, these features being obtained as the result of experiments with pumps of the type set forth, which herto have been far from satisfactory.

According to my invention a rotary pump of the type set forth comprises in combination a cylindrical housing or casing having formed in it an annular space within which is disposed a piston or radial blade member 15 adapted to be rotated through said space so as to travel about the cylindrical inner wall of said space, said piston or radial blade member being shaped so that it will engage and move once in every revolution in a substantially radial direction against the influence of spring means, a movable wall member disposed across a point in said annular space, said annular space having disposed in it either side of said wall member 20 inlet and outlet ports.

In order that my invention may be clearly understood and readily carried into effect I have appended hereto a sheet of drawings illustrating an embodiment of same, and 25 wherein:

Fig. 1 is a part sectional side elevation view.

Fig. 2 is a part sectional end view showing one half of the pump body removed to 30 show the interior of the pump.

Fig. 3 is an inner face view of one of the two elements constituting the movable wall member, and

Fig. 4 is an end sectional view of the 35 radial piston.

Referring to the drawings, a housing is provided constituted by a pair of circular members 1 and 2 united in axial alignment in any suitable manner and when so united 40 providing an enclosed annular chamber 3 around which is adapted to travel a radial blade or piston 4 secured to the periphery of a disc 5 carried by a shaft 6 supported for axial rotation in the housing. The shaft 55 6 can be rotated by any suitable means and a suitable packing gland 7 is preferably

provided to reduce leakage. In order to enable a compression or expansion action to be produced by the movement of the blade 4, a movable member 8 bridges across a part 60 of the annular chamber 3 so as to interrupt its continuity and to provide two end walls similar to bending a straight axis cylinder so as to bring its two ends together. This member 8 abuts into the inner periphery 65 of the chamber 3, and has its edge engaging such inner periphery curved so that the cam shaped radial blade 4 will ride evenly over it.

The member 8 is held pressed against the periphery of the disc 5 by spring plungers 9 the influence of which is overcome by the pressure of the piston 4 against the member 8 so as to raise it momentarily to allow the piston to commence another stroke. In Fig. 70 2 the piston 4 is rotating anti-clockwise and inlet and outlet ports 10 and 11 respectively are provided adjacent the member 8. It will be seen that the blade 4 effects a simultaneous expansion and compression stroke. 75

Referring more in detail to the various elements above described I will now introduce the more important features of such elements.

I have found in pumps of the type to 80 which this invention relates that a great loss in efficiency arises out of leakage past the edges of the piston 4 and to obviate this the piston 4 is grooved or channelled the full length of its free edge to receive a strip 12 85 which at all times during the working of the pump is maintained pressed by one or more springs 13 against the outer wall of the chamber 3. This strip 12 is preferably dovetailed in cross section, its inner face being the wider, the channel accommodating it being slightly larger but correspondingly shaped to receive the strip 12, whereby the strip 12 is safely held in position. 90

The ends of the piston 4 are recessed in a radial direction to receive end plates 14 (see more particularly Fig. 4) each of which is pressed out against the side walls of the annular chamber 3 to prevent leakage past the ends of the piston. The end plates 14 are reduced in width at their outer ends as indicated at 14a in Fig. 2 to engage in recessed or cut-away portions at the ends of the strip 12. 100

To prevent to a large extent any leakage 110 past the wall member 8, the inner edge of the said wall member is adapted to seat into

- a recess 8^a disposed across the inner concentric wall of the chamber 3 and at the same time engaging the periphery of the disc 5. The radial edges of the wall 8 also slide in 5 radial grooves 8^b disposed across the annular chamber 3 and continuous with the radial ends of the compartment 15 within which the wall 8 moves. By this means a nice sliding fit of the wall member 8 is obtained.
- 10 The springs 9^a of the plungers 9 are accommodated in radial cylindrical recesses 16 in the body of the pump, the said springs being disposed between flanges 9^b on the plungers 9 and in upper ends of hollow caps 17 threaded into the recesses 16. By this means the springs 9^a and plungers 9 can be removed when desired without disassembling the pump.
- 15 To ensure that the wall member 8 always has a tight fit in the chamber 15 so as to minimize leakage past the sides of the wall member as much as possible the wall member is preferably composed of two plates *a* and *b* (see Fig. 2) which have interposed between them a spring which may be an arcuate spring 18 secured to one of the plates and accommodated in registering horizontal channels 19 in the plates *a* and *b*. One plate (*b* in the drawings) overlaps the other plate at the upper end as indicated at *c*, the shorter plate (*a*) being shaped at its upper end as indicated at *d* to fit in a corresponding recess *e* across the plate *b*. The lower edge of the plate *b* is rounded 20 to ensure that the sloping side of the piston 4 will engage and raise the wall 8, the lower edge of this plate *b* overlapping the plate *a*. By this means the wall member 8 efficiently seals the space within which it works.
- 25 If desired the plungers 9 may be engaged in a rectilinear U section member the same width as the chamber 15 and resting upon the upper edge of the wall member 8 thereby sealing the space above the member 8 against the leakage of fluid into such space.
- 30 To effectively lubricate the shaft 6 an oil or grease chamber 20 is disposed in the body of the pump so as to communicate with the shaft bearings, the shaft if desired having helical or other peripheral grooves therein for lubricating purposes. A suitable lubricating cap is provided in the body for charging the chamber 20. A similar chamber 20 is preferably provided with the opposite end of the pump body adjacent the gland of the shaft 6.
- 35 The thickness of the plate 5 is very narrow compared with the width of the piston 4 so as to reduce as far as possible the gap 5^a in the inner concentric wall of the annular chamber 3, thereby obviating as far as possible leakage between the suction and delivery sides of the piston 4. To strengthen 40 the plate 5 it is preferably formed with a

concentric boss 21 upon both sides. The plate 5 is a ground fit in the body, and with a high efficiency pump the annular sides of the plate 5 can be fitted with expanding annular rings. 70

The direction of rotation of the piston 4 is indicated by the arrow in Fig. 2, and consequently the space in the annular chamber 3 between the outlet port 11 and the wall member 8 in the absence of any provision to 75 the contrary would be an idle space impairing the efficiency of the pump. To obviate this loss in efficiency, I provide a passage 22 communicating with the outlet 80 11 and the face of the wall member 8 which receives the pressure of the fluid being driven out by the moving piston 4. By this means practically all of the fluid drawn into the chamber 3 through the inlet 85 port 10 during one revolution of the piston, will during the next revolution of the piston be swept out of the outlet port 11. 85

Suitable lubricating passages 23 are provided in the cap 24 for admitting lubricating oil to the chambers 16 and 15, a suitable 90 lubricator being threaded into a recess 24 common to all of the passages 23.

If desired instead of a single wall member 8 a pair of symmetrically arranged wall members may be provided, one for each port 95 10 and 11, the distance between these two wall members being sufficient to ensure that one is disposed across the chamber 3 before the other is moved by the piston 4. This insures a thorough check on the closing of 100 the space between the valves 10 and 11. 95

I claim:—

1. A rotary pump comprising a cylindrical casing, concentric internally projecting bosses on the ends of the casing forming a 105 broad and comparatively shallow annular space between the periphery of the bosses and the periphery of the casing, a rotatable disc fitting between the bosses, a cam shaped piston mounted on the disc and fitting the 110 annular space, a slidable wall member engaging in grooves in the casing, resilient means to normally urge the wall member toward the periphery of the rotary disc, inlet 115 ports in the casing on one side of the movable wall member and outlet ports in the casing on the other side of the said movable wall member. 115

2. A rotary pump comprising a cylindrical casing, concentric internally projecting bosses on the ends of the casing forming a broad and comparatively shallow annular space between the periphery of the bosses and the periphery of the casing, a rotatable disc fitting between the bosses, a cam shaped piston mounted on the disc and fitting the annular space, packing strips located in the faces of the piston and pressed outwardly by resilient means to engage the walls of the annular space, a slidable wall member engaging 120 125 130

in grooves in the casing, resilient means to normally urge the wall member toward the periphery of the rotary disc, inlet ports in the casing on one side of the movable wall member and outlet ports in the casing on the other side of the said movable wall member.

3. A rotary pump comprising a cylindrical casing, concentric internally projecting bosses on the ends of the casing forming a broad and comparatively shallow annular space between the periphery of the bosses and the periphery of the casing, a rotatable disc fitting between the bosses, a cam shaped piston mounted on the disc and fitting the annular space, packing strips located in the faces of the piston and pressed outwardly by resilient means to engage the walls of the annular space, a slidable wall member engaging in grooves in the casing and formed in two pieces, interlocking ridges and grooves on the two parts, spring means between the two parts to press them apart and against the channels in which they may slide, resilient means to normally urge the wall member toward the periphery of the rotary disc, inlet ports in the casing on one side of the movable wall member and outlet ports in the casing on the other side of the said movable wall member.

4. A rotary pump comprising a cylindrical casing, concentric internally projecting bosses on the ends of the casing forming a broad and comparatively shallow annular space between the periphery of the bosses and the periphery of the casing, a rotatable disc fitting between the bosses, a cam shaped piston mounted on the disc and fitting the annular space, packing strips located in the faces of the piston and pressed outwardly by resilient means to engage the walls of the annular space, a slidable wall member engaging in grooves in the casing and formed in two pieces, interlocking ridges and grooves on the two parts, spring means between the two parts to press them apart and against the channels in which they may slide, overlapping upper and lower lips on one part, a rounded lower edge on the leading side of the wall member, resilient means to normally urge the wall member toward the periphery of the rotary disc, inlet ports in the casing on one side of the movable wall member and outlet ports in the casing on the other side of the said movable wall member.

5. A rotary pump comprising a cylindrical casing, concentric internally projecting bosses on the ends of the casing forming a broad and comparatively shallow annular space between the periphery of the bosses and the periphery of the casing, a rotatable disc fitting between the bosses, a cam shaped piston mounted on the disc and fitting the annular space, packing strips located in the

faces of the piston and pressed outwardly by resilient means to engage the walls of the annular space, a slidable wall member engaging in grooves in the casing, and formed in two pieces, interlocking ridges and grooves on the two parts, spring means between the two parts to press them apart and against the channels in which they may slide, overlapping upper and lower lips on one part, a rounded lower edge on the leading side of the wall member, at least one spring pressed plunger to normally urge the wall member toward the periphery of the rotary disc, inlet ports in the casing on one side of the movable wall member and outlet ports in the casing on the other side of the said movable wall member.

6. A rotary pump comprising a cylindrical casing, concentric internally projecting bosses on the ends of the casing forming a broad and comparatively shallow annular space between the periphery of the bosses and the periphery of the casing, a rotatable disc fitting between the bosses, a cam shaped piston mounted on the disc and fitting the annular space, packing strips located in the faces of the piston and pressed outwardly by resilient means to engage the walls of the annular space, a slidable wall member engaging in grooves in the casing and formed in two pieces, interlocking ridges and grooves on the two parts, spring means between the two parts to press them apart and against the channels in which they may slide, overlapping upper and lower lips on one part, a rounded lower edge on the leading side of the wall member, at least one spring pressed plunger to normally urge the wall member toward the periphery of the rotary disc, a removable cap to enclose the upper end of each spring pressed plunger, inlet ports in the casing on one side of the movable wall member and outlet ports in the casing on the other side of the said movable wall member.

7. A rotary pump comprising a cylindrical casing, concentric internally projecting bosses on the ends of the casing forming a broad and comparatively shallow annular space between the periphery of the bosses and the periphery of the casing, a rotatable disc fitting between the bosses, a cam shaped piston mounted on the disc and fitting the annular space, packing strips located in the faces of the piston and pressed outwardly by resilient means to engage the walls of the annular space, a slidable wall member engaging in grooves in the casing, and formed in two pieces, interlocking ridges and grooves on the two parts, spring means between the two parts to press them apart and against the channels in which they may slide, overlapping upper and lower lips on one part, a rounded lower edge on the leading side of the wall member, at least one

- spring pressed plunger to normally urge the wall member toward the periphery of the rotary disc, a removable cap to enclose the upper end of each spring pressed plunger,
- 5 inlet ports in the casing on one side of the movable wall member, outlet ports in the casing on the other side of the said movable wall member, and an auxiliary outlet port extending from near the movable wall into
- 10 the main outlet ports.
8. A rotary pump comprising a cylindrical casing formed in two parts split transversely to its axis, concentric bosses on each part forming a wide but comparatively shallow annular space between their periphery and the periphery of the casing, a shaft mounted in bearings in the bosses, a disc on the shaft and fitting between the ends of the bosses, a cam shaped piston projecting
- 15 from the periphery of the disc and fitting against the walls of the annular space, spring pressed packing strips in the piston faces, a slidable wall member formed of two pieces fitted face to face, interlocking ridges
- 20 and recesses on the two pieces, overlapping upper and lower edges to one piece, a rounded lower edge to the piece against which the cam-shaped piston engages, grooves in the walls of the casing and the periphery of the bosses in which the movable wall member engages, a recess in the casing into which the wall member may slide to permit the piston to pass, spring means between the pieces of the wall member to force them apart, plungers engaging against the outer end of the wall member, springs acting on the plungers so as to cause them to urge the wall member toward the axis of the pump, removable caps enclosing the outer ends of the said springs, inlet ports on the casing on one side of the wall member, outlet ports in the casing on the other side thereof, an auxiliary outlet port extending from near the wall member into the main outlet ports, and means for feeding lubricant to the wall member and to the interior of the pump and to the pump shaft.
- 25
